Henry M. Stearns
BY *Arthur L. Lee* ATTY.

UNITED STATES PATENT OFFICE.

HENRY M. STEARNS, OF RICHMOND, CALIFORNIA.

CEMENT WALL CONSTRUCTION.

Application filed October 20, 1924. Serial No. 744,656.

To all whom it may concern:

Be it known that I, HENRY M. STEARNS, a citizen of the United States, residing in the city of Richmond, in the county of Contra Costa and State of California, have invented a new and useful Improvement in a Cement Wall Construction, of which the following is a specification.

My invention relates to improvements in cement wall construction wherein a hollow core is permanently embedded within cement poured into a suitable wall formed to provide a continuous air space between spaced inner and outer wall portions.

As is well known, a double wall consisting of inner and outer wall portions separated by an air space is highly desirable because of its heat insulating properties and the effectiveness with which such a structure prevents moisture from penetrating through the wall. Such double wall structure is accomplished in numerous ways in the case of wooden and brick construction, but heretofore no fully satisfactory or commercially practical means has been devised for constructing such a double wall from cement or concrete, cement walls commonly being made solid or else built up from hollow blocks.

In cement block construction, the blocks are constructed with heavy webs formed at frequent intervals between the inner and outer wall portions and as a result the insulation afforded by the air spaces is of but slight benefit and moisture readily penetrates through the webs to the inner side of the wall. Furthermore, the blocks are bulky and top heavy so that the building of a wall from such blocks is a slow and relatively expensive means of construction.

The solid cement wall, formed by pouring cement directly into built up wall forms of suitable character is of course cheaper than the cement block construction, but the advantages of a hollow wall construction are entirely lost.

In the case of a cement wall, a double wall construction wherein the inner and outer wall portions are completely separated by a continuous air space is practically advantageous as a finishing coat of plaster may be applied directly upon the inner surface of the inner wall without the use of lath or furring and without danger of injury

due to the penetration of moisture through the wall.

My invention therefore has, as its primary object the providing of an improved construction to obtain a double cement wall, the inner and outer portions of which are fully separated by an air space.

Another object of my invention is to provide an improved wall construction which can be constructed economically and which will further reduce the cost of a building by permitting the wall to be surfaced directly upon the surface of the wall without the use of lath or furring.

A further object is to provide an improved core which may be readily mounted within a wall form and adapted to be permanently embedded to form a continuous air passage between the inner and outer wall portions formed when the form is filled.

A still further object is to provide an improved insulating core built in sections which may be readily assembled and which will insure a correct matching of adjacent edges of adjacent sections.

A further object is to provide an improved core provided with means for retaining the wall of the core and of the form in properly spaced relation and which will serve to bond together the inner and outer wall portions of a cement wall.

A still further object is to provide an improved core which may be economically manufactured and which can be permanently embedded within a cement wall to afford an improved wall construction at a very low cost.

I accomplish these and other objects by means of the improved wall construction disclosed in the drawings forming a part of the present specification wherein like characters of reference are used to designate similar parts throughout said specification and drawings and in which,

Fig. 1 is a broken elevation of a portion of a wall constructed in accordance with my invention, portions being broken away to disclose the structure of the wall.

Fig. 2 is a horizontal section of a portion of a wall showing the manner in which the wall is formed within a wall form.

Referring to the drawings the numerals 1 and 2 are used to designate the inner and outer portions respectively of a cement

wall having a hollow core, designated in general by the numeral 3, forming a continuous air passage therebetween.

The core 3 is formed from a plurality of 5 sections each consisting of a pair of walls held in parallel spaced relation by means of spacing elements 4 mounted therebetween, saids walls being rectangular in form and made from any suitable material such as 10 light wall-board. The spacing elements 4 consist of strips of wood or wall board of suitable width to obtain the desired spacing between the walls, said strips extending outwardly past the edges of the walls for a purpose 15 hereinafter more fully explained.

The wall is constructed by building a suitable form 6 in the manner commonly employed in the building of solid cement walls, the core 3 being mounted between the sides 20 of the form by assembling the core sections together as the form is erected. Spacers 7 are applied in connection with the core sections to hold the sections in a desired position between the walls of the form and to 25 hold the sides of the form in a desired spaced relation, the sides of said form being drawn against the ends of the spacers in the well known manner to obtain a uniform spacing of the form.

30 In assembling the core 3 the sections are placed with their ends and sides abutting against the adjacent ends or sides of adjacent sections. The sections are preferably staggered and the outwardly extending ends 35 of the spacing strips 4 caused to enter between the adjacent wall portions of an adjacent section as shown in Fig. 1 of the drawings, thereby insuring an accurate matching of the walls and holding the sections in assembled relation. At the corners of a building, the core 3 of one wall is caused to abut 40 against the core of the wall at right angles thereto as shown in Fig. 2 of the drawings whereby the core is extended without interruption around the corner.

45 After the form and core have been built, wet cement is poured in the ordinary manner to fill the spaces between the core and the sides of the form, the core being fully embedded in the poured cement and forming a 50 continuous air passage between the inner and outer portions of the wall. The spacing elements 4 are spaced at intervals of from three to six inches, depending upon the weight of 55 material used to form the walls of the sections 3, said spacing elements being arranged sufficiently close together to sustain the weight of the cement and prevent the collapse of the core when the form is filled. 60 The spacers 7 are embedded within the cement upon both sides of the core as the form is filled.

When the cement has become set, the wall form 6 is taken down as in ordinary practice, the core 3 being left embedded within

the center of the wall. After the form has been removed the wall portions stand as a self sustaining structure presenting the outward appearance of the ordinary solid cement wall but provided with a continuous 70 air space between said portions, the inner and outer wall portions 1 and 2 being effectively bonded together by means of the spacers 7, the ends of which are permanently embedded within the cement in opposite wall 75 sections.

In my present practice, the core sections 3 are constructed of relatively light weight card-board. This material is relatively cheap thus permitting the sections to be 80 manufactured at a very low cost whereby the core may be permanently embedded within the wall at a cost little, if any, greater than the cost of a solid wall of the same dimension. After the cement has set it is immaterial whether the core disintegrates or not, thus making the selection of a durable or rot resisting material unnecessary.

The above described wall structure is particularly adapted for the building of homes 90 and cottages. In this connection, the double cement wall formed is adapted to receive an interior finishing coat of plaster applied directly upon the cement without the expense of applying lath or furring of any kind. 95 This is rendered possible as the heat insulation obtained by the double wall structure avoids subjecting the plaster to stress due to expansion and contraction resulting from changes in temperature, and also prevents 100 absorption of moisture through the wall such as would tend to loosen the plaster. In like manner a finishing dash coat of stucco or other suitable finishing material may be applied directly upon the outer surface of the 105 wall without the use of lath or furring. In this manner a very great saving may be effected in the cost of construction and at the same time obtain a lighter and warmer 110 house.

Having thus described my invention what I claim as new and desire to secure by Letters Patent is,

1. A hollow core for a cement wall consisting of a plurality of core sections each having a pair of walls formed from light wall-board and provided with a plurality of spacing elements secured between said walls to hold the same in spaced parallel relation, the ends of said spacing elements extending outwardly past the edges of the walls to be engaged between the walls of adjacent sections whereby said sections may be assembled and held with the edges of each section matching with the adjacent sections.

2. A hollow core for a cement wall consisting of a plurality of core sections each having a pair of walls formed from light wall-board and provided with a plurality of spacing elements secured between said walls

110

115

to hold the same in spaced parallel relation, the ends of said spacing elements extending outwardly past the edges of the walls to be engaged between the walls of adjacent sections whereby said sections may be assembled and held with the edges of each section matching with the adjacent edges of adja-

cent sections; and means for holding the core in spaced relation to the sides of a wall form whereby the core may be enclosed within the wall when cement is poured into the form. 10

In witness whereof I hereunto set my signature.

HENRY M. STEARNS.
